UNITED STATES PATENT OFFICE

ALBERT L. C. RINGEL, OF ALTOONA, PENNSYLVANIA

RADIO RECEIVING SET

Application filed January 19, 1931. Serial No. 509,762.

The invention relates to a radio receiving set, and more particularly to a station indicator or dial construction for radio receiving sets.

5 The primary object of the invention is the provision of a construction of this character wherein a spherical dial is supported to afford a logging chart of maximum area and in which is arranged the radio receiving equipment, the dial being exteriorly mapped or decorated, in this instance, indicative of the hemispheres of the world and readily selectively operated for bringing in broadcasting stations working on varying wave lengths 10 or meters.

Another object of the invention is the provision of a construction of this character, wherein the make-up thereof is novel in form and is attractive and unique in character.

20 A further object of the invention is the provision of a construction of this character which is extremely simple, thoroughly reliable and efficient in operation, compact, neat in appearance and inexpensive to manufacture.

With these and other objects in view, the invention consists in the features of construction, combination and arrangement of parts, as will be hereinafter more fully described 30 in detail, illustrated in the accompanying drawings which disclose the preferred embodiment of the invention, and pointed out in the claims hereunto appended.

35 In the accompanying drawings:—

Figure 1 is an elevation of a radio receiving set constructed in accordance with the invention.

Figure 2 is a sectional elevation taken on the line 2—2 of Figure 1.

40 Figure 3 is a horizontal transverse sectional view.

Figure 4 is a fragmentary sectional view taken on the line 4—4 of Figure 2, looking in the direction of the arrows.

45 Figure 5 is a fragmentary detail view showing a heat emitting screen associated with the set.

Figure 6 is a fragmentary plan view at the 50 revolving point of the dial or station selector of the set.

Similar reference characters indicate corresponding parts throughout the several views in the drawings.

Referring to the drawings in detail, the 55 radio receiving set comprises a stand A which preferably includes a base 10 of circular contour supported upon feet 11 which are continuations of columns or posts 12 supporting a circular guard or rail 13 elevated the required height from the base 10 of the stand. 60

At a suitable point centrally of the base 10 is arranged a loud speaker 14 of any approved type and upon the top of this speaker 14 is suitably fixed a bearing 15 having detachably mounted therein a forwardly inclined tubular axle 16, to the upper end of which is fixed a suitable mounting 17 for a radio receiving mechanism 18 of any approved or standard construction. 65

70 Enclosing the receiving set 18 and within the guard rail 13 of the stand is a spherical hollow body 19 of the required size, preferably made in separable half sections and made from opaque material having the outer surface thereof decorated or mapped, in this instance indicative of the world, as at 20.

75 On the axle 16 is journaled a gear 21, the latter supporting the body 19 and this gear is included or in mesh with a train of planetary operating gears 22, one of which being operatively connected to the condensers of the receiving set 18, so that on the turning of the body 19, the condensers of the receiving set 18 will be simultaneously adjusted. It is, of 80 course, understood that the speaker 14 is in electrical connection with the receiving set 18 and has its connections 23 trained upwardly through the hollow axle 16 to said set, as shown in Figure 2 of the drawings. 85

90 The spherical body 19 has arranged internally thereof and stationarily mounted a partition or shield 24 which divides the said body into two chambers or cells 25 and 26 respectively, while arranged between the sections of said body and encircling the latter for exposure externally thereof is a scale band 27 having degree marks 28 on its outer face indicative of the meters of wave lengths, the band being made from translucent material. 95 Mounted on the partition 24 and disposed 100

close to the band 27 to co-extend with substantially one-half of its circumference is a light obliterating shield, guard or mask 29, for a purpose presently described.

6 The shield 29 extends rearwardly from the partition 24, while mounted on and projected forwardly of said partition 24 is a triangular shaped shield or screen 30, the forward apex 31 of which coincides with the center of the frontal portion of the band 27 in close relation thereto to effect a shadow casting medium to function as a pointer or indicator co-acting with the scale 28 on said band, in a manner as presently described.

10 15 Suitably arranged on the partition 24 contiguous to the outer faces of the sides of the triangular shaped shield 30 are electric bulbs 32, these being arranged in a suitable electric circuit in the equipment of the radio receiving set 18, and by reason of the forwardly converging sides of the shield 30, the light rays from said lamps or bulbs are projected toward the band 27 so that the tip or apex 31 will break the light rays and form a dark spot upon the band to have the said tip or apex 31 cause a shadow at its locality directly upon the band which will be visible distinctly through the same and thus serve as a pointer or indicator, the top and bottom plates 33 and 34 on 20 25 30 the shield 30 confining the beam of the light between said plates, as will be clearly obvious from Figure 2 of the drawings.

35 The body 19, concentrically of the hub of the gear 21, is formed with an opening 35 to emit heat from the interior of said body, while diametrically opposite this opening in the body 19 is another screened opening 36 which permits the escape of heat from within the body. Also the body at suitable intervals throughout the extent of the sphere is 40 45 perforated at 37 indicative of broadcasting stations in determined areas of the map 20 on the outer face of said body.

50 In the operation of the receiving set, to effect accurate tuning or the selection of broadcasting stations for the operation of the set, the body 19 is manually manipulated so that a selected degree in the scale 28 on the band 27 will be brought into register with the pointer constituted by the apex 31 of the shield 30 which pointer throws a shadow therefrom onto the band by dividing the illumination from the bulbs 32 and in this manner a predetermined broadcasting station will be tuned in, as on manual turning of the body, the train of gears 22 simultaneously operating the condenser within the receiving set 18 which as previously stated can be of any standard equipment.

55 60 Made fast to the top of the loud speaker and encircling the spherical body 19 is the meridian ring 38 ordinarily employed as a part of a revolving whirl globe.

65 In the use of the radio set, it will be apparent that those portions of the band, the

opposite sides of that traversed by the pointer 31 will be illuminated for one-half of the circumference of the body, while the remaining portion of said band will be obscured or unlighted and the pointer or indicator 31 70 through a shadow cast therefrom. Such shadow will be visible exteriorly of the body 19 upon the band for enabling accuracy of tuning in this radio set in selecting various located broadcasting stations. 75

The space between the plates 33 and 34 confining the light from the bulbs 32 opens rearwardly of the body 19 and this light is obliterated from the band 27 confronted by the shield 29 and it will be obvious that the rear half of the body beyond the area of the shield 80 interiorly of said body is lighted.

What is claimed is:—

1. In a radio receiving set, a stand, a loud speaker on the stand, a revoluble sphere supported upon the stand and having an externally mapped surface, a meter band of translucent material encircling the sphere and carried thereby, means within the sphere for lighting a portion of the band, a radio receiving mechanism within the sphere, means for tuning said mechanism on rotation of the sphere and means within the sphere to create a dark spot and visible through the meter band in the lighted portion thereof. 95

2. In a radio receiving set, a stand, a loud speaker on the stand, a revoluble sphere supported upon the loud speaker and having an externally mapped surface, a meter band of translucent material encircling the sphere and carried thereby, means within the sphere for lighting a portion of the band, a radio receiving mechanism within the sphere, means for tuning said mechanism on rotation of the sphere, a stationary pointer within the sphere and visible through the meter band, and illuminating means having its rays confined to the pointer for casting a shadow therefrom onto the band in the lighted portion thereof and interiorly of said sphere. 110

3. In a radio receiving set, a stand, a loud speaker on the stand, a revoluble sphere supported upon the loud speaker and having an externally mapped surface, a meter band of translucent material encircling the sphere and carried thereby, means within the sphere for lighting a portion of the band, a radio receiving mechanism within the sphere, means for tuning said mechanism on rotation of the sphere, a stationary pointer within the sphere and visible through the meter band, illuminating means having its rays confined to opposite sides of the pointer and interiorly of said sphere, a partition within the sphere and shielding the illumination from a portion of the sphere, and a shield confronting one-half of the extent of said meter band. 125

4. In a radio receiving set, a stand, a loud speaker on the stand, a revoluble sphere sup- 130

ported upon the loud speaker and having an externally mapped surface, a meter band of translucent material encircling the sphere and carried thereby, means within the sphere for lighting a portion of the band, a radio receiving mechanism within the sphere, means for tuning said mechanism on rotation of the sphere, a pointer within the sphere and visible through the meter band, illuminating means interiorly of said sphere and having its rays confined to opposite sides of the pointer for its shadow cast upon the band, a partition within the sphere and shielding the illumination from a portion of the sphere, a shield confronting one-half of the extent of said meter band, gear connections between the sphere and said radio receiving mechanism, a guard rail on the stand and encircling the sphere, said sphere being perforated at determined locations indicative of broadcasting stations.

In testimony whereof I affix my signature.
ALBERT L. C. RINGEL.
